UNITED STATES PATENT OFFICE

MARY E. THOMPSON, OF NEW YORK, N. Y., ASSIGNOR OF ONE-HALF TO
CHARLES D. THOMPSON, OF SAME PLACE.

PORTABLE DUST-HOOD AND BLOWER.

SPECIFICATION forming part of Letters Patent No. 328,087, dated October 13, 1885.

Application filed December 9, 1884. Serial No. 149,908. (No model.)

To all whom it may concern:

Be it known that I, MARY E. THOMPSON, of the city, county, and State of New York, have invented a certain new and useful Improvement 5 in Portable Combined Dust-Hoods and Blowers for Open Fire-Places or Grates; and I do hereby declare that the following is a full, clear, and exact description thereof, reference being had to the accompanying drawings, making a part of this specification.

The object of my said invention is to provide a portable hood to confine the dust, ashes, and smoke which are caused to arise by the taking up of ashes in grates, removing the 15 cinders therefrom, cleaning such grates, &c., in open fire-places, to such fire-places, and preventing such dust, ashes, and smoke from escaping into the room and settling upon the walls or furniture thereof, or permeating or 20 disfiguring any of the articles, useful and ornamental, contained in such room, and at the same time to adapt such hood to act as a blower, when desired.

The fact is well recognized that great 25 comfort and inconvenience of the person and injury to property is caused by the arising, escape, and distribution of dust, dirt, ashes, and smoke throughout a room every time the grate is cleaned or disturbed, especially when 30 coal is used as a fuel; and the object of my invention is, principally, to avoid these effects by the use of a blower so constructed that it can be extended, when desired, to form a hood of any desired size, and can thus be applied to 35 any of a number of fire-places having grates of different sizes. For this purpose I form a hood, preferably of sheet-iron; but it can be made of paper or other suitable material, so its rear end or side will fit closely or impinge against 40 the mantel, or immediately in or above the fire-opening, and will extend out into the room above the grate about eighteen inches, or as far as it is necessary or may be desirable. The side of this hood should extend downward 45 about to the top of the bars of the grate. This hood may be held in place by any suitable means, as by eyes upon the rear side of the hood fitting into permanent hooks formed in the mantel-frame, or by a broad hook or clamp 50 upon the rear side of the hood, so that it may be hooked or clamped into the fire-place, as

shown. These supports may be so constructed that when necessary they can be lengthened or shortened, and the hood can be formed in hinged or sliding sections, preferably at the 55 side sections, so that it can fold or slide together, so as to form an ordinary blower and be used only for the purpose of a blower.

In the accompanying drawings, Figure 1 is a perspective view of my hood in position for 60 use upon the mantel or grate, A being the hood, which may be square or oval in shape; and B, the preferable form of support when the hood is in place; C C', the sliding section to form the blower.

Fig. 2 represents another form of support and sectional adjustment. Catches and pins are provided, as shown, upon the side sections, engaging with each other, and enabling the sections to be readily drawn out into their 70 extended positions, where they are held by the friction and mutual strain of the parts upon each other.

In operation as a hood it is placed in position as shown in Fig. 1. The operator can 75 then remove all the contents of the grate to the scuttle standing under the hood, or clean out the grate, as it may be desired, and no dust or ashes will or can escape into the room, as it is either deflected up the chimney or falls 80 immediately down and is brushed back into the fire-place.

This portable dust-hood and blower can be carried from room to room, and one hood will serve the purpose of a whole house. No exact 85 fit is requisite, and a hood suitable for the largest grate in the house will answer well for the smaller grates.

I do not intend to confine myself to the exact form of detailed devices for holding the 90 hood or blower in place, or of the hinged or folding sections thereof, as they can be easily attached without in the least changing my invention.

What I claim as my invention, and desire 95 to secure by Letters Patent, is—

1. A portable dust-hood and blower having sides formed in sections, pivoted together at one end, the front of the blower being composed of a single sheet, substantially as described and shown.

2. A portable dust-hood and blower having

a front composed of a single sheet, sides formed in sections, pivoted together at one end, and stops and catches upon the side sections, engaging with each other and operating to effect 5 the extension of the sections, substantially as described and shown.

3. In a combined dust-hood and blower, the combination of a front piece, sides made in sections, said side sections being pivoted to-

gether at one end thereof, and an eye attached to the upper part of the front piece for supporting the blower over the grate, substantially as described and shown.

MARY E. THOMPSON.
